United States Patent Office

Des. 197,387
Patented Jan. 21, 1964

197,387

DECANTER

Charles B. Smith, 4157 N. Clarendon Ave.,
Chicago 13, Ill.

Filed Nov. 1, 1962, Ser. No. 72,337

Term of patent 14 years.

(Cl. D58—9)

FIG. 1 is a front perspective view of a decanter, showing my new design;

FIG. 2 is a rear perspective view; and

FIG. 3 is a vertical section from the rear, taken on the line 3—3 of FIG. 2.

I claim:

The ornamental design for a decanter, as shown.
